CIRCUIT INTERRUPTER

Jerome Sandin, Forest Hills, and Bryan B. Paul,
Pittsburgh, Pa., assignors to Westinghouse Electric & Manufacturing Company, East Pittsburgh, Pa., a corporation of Pennsylvania

Application December 31, 1937, Serial No. 182,780

16 Claims. (Cl. 200—144)

This invention relates to improvements in the construction of electrical apparatus and more specifically to arc extinguishing structures for circuit interrupters. The construction of electrical apparatus involves the use of both conducting and insulating materials. Certain insulating as well as conducting members of a particular piece of electrical equipment may at some time or other be subjected to an arc either accidentally or by design. The insulating wall members of an arc extinguisher and the arcing contacts of a circuit interrupter are examples of the use of materials designed to be acted upon by an arc whereas the line terminals or other conducting members, as well as the insulating or metallic support structure of a circuit breaker are examples of the use of materials which may be subjected to an arc accidentally.

It is well known that if an arc strikes to or forms a terminal upon a metallic member, the member may be burned or decomposed to such an extent that it can no longer perform its intended function. We have discovered that when metallic members are coated with a gas producing material such as boric acid, an arc closely adjacent will decompose the coating material, forming a blast of gas about the member which repels the arc, thereby preventing the arc from forming a terminal upon the conducting member. To provide such a gas emitting coating upon the conducting members of electrical apparatus is therefore one of the objects of our invention.

A refractory material as porcelain is known to have good arc resisting properties and remains a good insulator even after repeated direct influences of arcing. The refractory materials, however, are not suitable in many instances since they have a low tensile strength, are brittle and incapable of withstanding considerable shock. Organic or fibrous materials, on the other hand, in addition to the requisite insulating properties, have the advantage that they can be easily formed into the desired shape and have inherently highly mechanical strength. The insulating properties of fibrous materials in general, however, may be destroyed by the repeated subjection of these materials to an arc. Some of these materials are also readily consumed by an arc and give off gases which interfere with the extinction of an arc.

A further object of our invention is to provide means for preserving the insulating properties of fibrous material employed in the construction of electrical apparatus and which are either occasionally or repeatedly subjected to an arc.

5 A more specific object of our invention is to improve the arc resisting properties of fibrous insulating members of arc extinguishing structures. This may be done by impregnating the fibrous insulating members with a gas producing material which gives off a gas when acted upon by an arc, thereby repelling the arc and preventing it from impinging upon the insulating surface.

10 Another specific object of our invention is to improve the arc extinguishing function of circuit interrupters employing arc chambers of porous insulating material which decomposes when acted upon by an arc to produce an ionizing blast of gas for extinguishing the arc. We have found that improved results can be obtained by impregnating the porous insulating material with a substance such as boric acid which when acted upon by an arc, decomposes and produces a blast of water vapor which is highly effective in deionizing the arc.

15 This and other objects and advantages will appear more fully in the following description when read in connection with the accompanying drawings in which:

20 Figure 1 is a plan view of a circuit interrupter embodying the features of our invention and which has a portion of its cover broken away to reveal one of the arc extinguishing structures and a portion of the operating mechanism.

25 Fig. 2 is a side elevation view of the circuit interrupter of Fig. 1 showing a portion of the casing broken away and the arc extinguishing structure in longitudinal section.

30 Fig. 3 is an enlarged sectional view through an arc extinguishing structure of our circuit interrupter.

35 Fig. 4 is an elevational view of the arc extinguishing structure as viewed from the arc receiving end of the structure.

40 Fig. 5 is a plan view showing a modified arc extinguishing plate structure.

45 Fig. 6 is a sectional view of the plate structure shown in Fig. 5 taken along the line VI—VI, and

50 Fig. 7 is an elevational view, partially in section, showing the application of our invention to an explosive circuit interrupting device.

55 Referring to the drawings, the reference numeral 10 designates a base of a three-pole circuit interrupter of the type shown and described in the application of Jerome Sandin, Serial No. 182,484, filed December 30, 1937, and assigned to the assignee of this application. The base 10 is divided into three compartments 12, only one of

which is shown, for receiving the respective poles of the interrupting structure. Each pole of the circuit interrupter comprises a fixed contact 14 and a movable contact 16 yieldingly supported upon the end of a contact arm 18 mounted for swinging movement about shaft 20. The fixed contact 14 is connected by a conductor 22 to a connector 24. The connector 24 is provided with a threaded stud 26 for clamping one of the line terminals 28 thereto. The movable contact 16 is connected by a flexible conductor 30 to a suitable electro-responsive device, not shown, for tripping the pole unit mounted in the compartment 12. The electrical circuit from the electro-responsive tripping device terminates at the other line terminal 32 of the interrupter.

The movable contact arms 18 are preferably insulatingly secured to a tie bar 34 which cooperates with a snap acting operating mechanism, not shown, including a hand operating lever 36 for moving the respective contacts 16 to open and closed positions. Each pair of contacts 14 and 16 are partly surrounded by an arc extinguishing structure comprising a pair of wall members 38 of porous insulating material. The opposed inner surfaces and the wall members 38 are provided with slots or channels for receiving the side edges of a plurality of conducting plates 40. The plates 40 have a V-shaped groove or slot formed in one end thereof as shown in Fig. 5. As shown more clearly in Figs. 2, 3 and 4, the plates 40 are more closely spaced at their slotted ends and are arranged with their slots in superimposed relation so as to form an aligned groove. Inasmuch as the plates 40 converge towards their slotted ends, some of the plates are somewhat shorter than the others in order to maintain sufficient spacing between the ends of the plates to prevent insulation failure. The wall members 38 are held in clamping engagement with the plates 40 by means of rivets 42 passing transversely therethrough so as to unite the plates and wall members in a unitary structure.

The wall members 38 are also provided with indentations or recesses extending from the outer surface inwardly at 44 so as to provide an intermediate shoulder portion 46 having a vertical bore 48 therethrough for receiving a suitable mounting screw 50. The mounting screw 50 is adapted to be screwed into the base 10 thereby securely holding the arc extinguishing structure in proper relation with respect to the contacts 14 and 16.

The arc extinguishing plates 40 are preferably of magnetic material such as iron so that when the arc is drawn between the contacts 14 and 16 as a result of movement of the contacts 16 through the groove formed by the slots in the plates 40, the magnetic reaction set up by the plates 40 will move the arc towards the apex of the slots and into the plates. The plates 40 thus split the arc into a plurality of short serially related arcs and extinguish the same by defionizing the arc stream in a manner which is well known in the art. In order to prevent extremely heavy current arcs which travel with relatively high velocities, due to the magnetic actions set up in the plates, from moving beyond the ends of the plates 40 and restriking into a single arc, two transversely disposed barriers 52 are provided between the wall members 38 as more clearly shown in Figs. 2 and 3. The barriers 52 are disposed at medial points along the arc path, so that in the event the short arcs succeed in passing through the plates and tend to restrike as a single arc

along the outer edges of the plates, there will be a sudden lengthening of the arc at the barriers 52, causing the arc to be extinguished.

The opposed surfaces of the side wall members 38 adjacent the arc receiving slots in the plates 40 taper inwardly in the direction of arc movement so as to provide a convergent entrance passage for the arc. The narrow constricted portion between the opposed wall members 38 extends a considerable distance along the arc receiving slots and again widens in the direction of arc movement, as more clearly shown in Fig. 1. The tapering entrance portion as provided by the side walls 38 serves to contract the arc so as to facilitate entry of the arc into the plates 40. The inwardly projecting portions of the side walls 38 also serve to imbed the metallic portions of the plates 40 adjacent the sides of the slots. This construction lessens the tendency of the arc to strike to an intermediate plate along the side edges of the slot prior to movement of the movable contact 16 to its full open position. Also, if an arc were permitted to impinge on the plates at a point along the side edges of the slot, further arc movement would likely be prevented and failure of the structure would result.

Even though the edges of the plates adjacent the slot are not directly exposed to the arc, there is a tendency for the arc to move laterally from side to side of the slot, thus causing rapid deterioration of the side walls of the members 38. The members 38 are preferably formed of a cold molded material constituting 22% hydrated lime, 38% powdered silicate and 40% asbestos fibre. Although this substance has excellent heat resisting properties and is a good insulator, the repeated action of an arc playing upon the side walls defining the arc passage causes the side walls to blister and eventually causes a material lowering of resistance. In order to prevent the deleterious effect of the arc upon the side wall members, we impregnate the wall members with a substance which produces a gas when acted upon by an arc, so as to repel the arc and maintain it centrally of the passage during its movement into the plates 40.

Although the cold molded material above described is preferred, other cold molded materials may be used, such as a composition comprising 50% Portland cement and 50% asbestos fiber or a composition comprising 50% Portland cement, 15% barytes and 35% asbestos fiber. Horn fiber is also suitable as a material from which the wall members 38 may be constructed. A porous refractory material comprising 30% talc, 2% feldspar and 68% clays is also suitable but less desirable than the cold molded materials since it is more brittle and less capable of withstanding shock.

The fibrous composition from which the wall members 38 are composed is preferably impregnated in the following manner: Prior to assembly of the wall members with the plates 40, the members are immersed in a saturated solution of boric acid and allowed to remain in that solution for a time sufficient to enable the members to absorb a considerable quantity of the solution. The members are then removed and dried at a temperature below that at which boric acid decomposes for a period of time sufficient to remove substantially all moisture. If necessary, additional impregnating treatments as above described may be employed to increase the amount of boric acid deposited in the voids of the members. We have found that for the particular

members described, immersion in a concentrated solution of boric acid for at least 30 minutes, followed by a drying period of about four hours at a temperature of 120° C. is sufficient to impregnate the members. The boric acid particles with which the side wall members 38 are impregnated are schematically illustrated at 53 in Fig. 4.

The use of boric acid in the solid form as a liner for arc passages in explosive circuit interrupters is well known. We have discovered that solid boric acid as a liner of the side walls of the entrance passage of an arc extinguisher of the type herein disclosed is undesirable in that it produces such a turbulent blast of gas in the entrance passage so as to interfere with the arc movement into the deionizing plates. By impregnating the side walls of the arc passage with boric acid just sufficient gas is liberated, which is directed against the arc stream in the presence of the arc, to maintain the arc out of contact with the walls. The presence of the water vapor resulting from the action of the arc upon the boric acid does not interfere with arc movement by the magnetic reaction set up by the magnetic plates and is further beneficial in that it assists in deionizing the arc stream. Although we prefer to impregnate the insulating wall members 38 with a solution of boric acid, other materials such as gypsum

and ammonium alum

may be used, but with somewhat inferior results. Both gypsum and ammonium alum produce liberal quantities of water vapor when acted upon by an arc but are less desirable than boric acid since they have a relatively low resistance when in the molten state. Boric acid on the other hand, retains its insulating properties even when it is in the liquid state and for this reason it is preferred as the impregnating substance.

As shown in Figs. 1 and 2, a barrier 54 of fibrous material is inserted between the end of the arc extinguishing structure and the conductor 22 and connector 24. The barrier 54 is also preferably treated with boric acid solution so that in the event an arc should impinge thereupon a gas will be liberated which repels the arc and also assists in its extinction. The presence of boric acid in the barrier member 54 is shown at 55 in Fig. 2. We have also discovered that the metallic conducting parts of the breaker such as the movable contact arm 18, conductor 22, connector 24, screws 26 and terminal members 28 and 32 may be coated with boric acid as by dipping these parts in a saturated solution of boric acid or by spraying the saturated solution of boric acid thereon. The metallic surface of these members retains a sufficient quantity of boric acid, so that when an arc tends to strike thereto the boric acid will be decomposed surrounding the metallic conductor with a blast of water vapor which repels the arc and prevents the formation of an arc terminal upon the conducting member. In this manner the conducting members are protected from decomposition by the arc in the event that an arc should accidentally strike thereto.

In Figs. 5 and 6, a modified form of plate structure is shown which may be employed with side wall members 38 in the arc extinguisher previously described. Instead of using a single plate of magnetic material having considerable thickness, two thinner plates 60 and 62 are employed having a thin layer of solid boric acid indicated

5 at 64, interposed therebetween. It is desirable to confine the use of boric acid mainly to the portions of the plates 60 and 62 adjacent each side of the V-shaped slot. The presence of boric acid immediately adjacent the closed end of the slot may cause the generation of sufficient gas to prevent the movement of the arc into the plates 60 and 62. The presence of the thin layer of boric acid 64 along the side edges of the slot performs the same function as the boric acid impregnated in the side walls 38 of the arc extinguishing structure. That is, a small quantity of water vapor is released by the action of the arc and directed against the arc so as to maintain the arc centrally positioned as it moves into the deionizing plates of the arc extinguishing structure.

The further embodiment of our invention is shown in Fig. 7 in which the numeral 70 designates a tube of a fibrous material such as horn fiber defining the arc passage of an explosive circuit interrupter. The upper end of the tube 70 is provided with a metallic ferrule 72 which is threaded for the reception of a cap 74 which serves to hold a button 76 of a fuse link 78 in engagement with the ferrule. The cap 74 also securely seals the upper end of the tube 70. The lower end of the fuse link 78 is provided with a flexible conductor 80, the end of which extends through the open end of the tube 70 and is secured to a metallic ferrule 82 by means of a thumb screw 84. Tube 70 of fibrous material is preferably impregnated with a saturated solution of boric acid, the boric acid being indicated at 86. Thus when the arc is established within the tube 70 as a result of blowing of the fuse link 78, it decomposes a portion of the tube 70, creating a deionizing blast of gas which extinguishes the arc with an explosive action. The presence of the boric acid within the walls of the tube 70 increases the gas generated and hastens the arc extinguishing process, thereby materially decreasing the deteriorating effect of the arc upon the tube. Boric acid is particularly effective in that upon decomposition it liberates water vapor which is a good deionizing agent.

15 In this connection it should also be understood that the tube 70 may be impregnated with other materials such as gypsum or ammonium alum above referred to. However, due to the lower resistance characteristic of these materials when

30 they are in the molten condition renders them less desirable for this particular purpose than boric acid.

55 Although we have shown and described specific materials and structures for the purpose of carrying out our invention, it shall be understood that the same is for the purpose of illustration, and that other materials than those named could be used for coating metallic members or for impregnating porous insulating materials to achieve the objects sought in this invention, and that we do not wish to be limited by said illustrations except as specifically set forth in the appended claims.

60 We claim as our invention:

1. In a circuit interrupter, an arc chute comprising a pair of spaced wall members of porous inorganic insulating material, said wall members having a portion of their opposed surfaces adjacent one end tapering towards each other to provide a converging entrance passage, a plurality of spaced metallic plates disposed between said wall members, and means for moving an arc from said entrance passage into said plates, said wall members being impregnated with a solution of a material which gives off a gas when

acted upon by an arc to provide a flow of gas against the arc to maintain it centrally of said wall members as it moves into said plates.

2. In a circuit interrupter, an arc chute comprising a pair of spaced wall members of refractory insulating material, said wall members having a portion of their opposed surfaces adjacent one end tapering towards each other to provide a converging entrance passage, a plurality of spaced metallic plates disposed between said wall members, said plates being composed of a ferrous material and having a V-shaped slot in one end thereof, portions of said plates adjacent their slots being completely recessed in said tapering portions of said wall members, and means for establishing an arc in said entrance passage, said arc being moved towards the closed end of said slots and into said plates by the magnetic reaction set up thereby, said wall members being impregnated with a solution of material which gives off a gas when acted upon by an arc to provide a flow of gas against the arc to maintain it centrally of said wall members as it moves into said plates.

3. In a circuit interrupter, means for opening the circuit to establish an arc, an arc extinguishing device in which said arc is established, said arc extinguishing device comprising a plurality of plates of magnetic material, said plates having a V-shaped slot in one end thereof, said arc being moved into said plates by the magnetic reaction set up by said plates, a pair of unitary side wall members of cold molded insulating material impregnated with a solution of boric acid, said wall members having spaced longitudinally extending grooves for receiving the side edges of said plates, and means for holding said side wall members in clamping engagement with said plates, said boric acid emitting a blast of water vapor when said arc impinges upon said side wall members which blast of vapor maintains the arc centrally positioned with respect to said wall members and aids in extinguishing the arc.

4. An arc extinguishing device for circuit interrupters comprising a plurality of pairs of plates of conducting material, said plates having a V-shaped arc receiving slot in one end thereof, a thin layer of material which gives off a gas when acted upon by an arc disposed in contiguous relation between each pair of plates at least between the greater portion of said plates adjacent the sides of said slots, and means for supporting said pairs of plates in spaced relation with respect to each other.

5. An arc chute for circuit interrupters comprising a pair of wall members of insulating material, a plurality of plates of conducting material disposed in spaced relation between said wall members, said plates having an arc receiving slot in one end thereof, some of said plates being spaced more closely than others, and a material which gives off a gas when acted upon by an arc between said more closely spaced plates at least along the greater portion of the sides of said slots for causing a blast of gas against an arc playing in said slots to maintain the arc positioned centrally of said slots.

6. An arc chute for circuit interrupters comprising a pair of wall members of insulating material, a plurality of plates of conducting material disposed in spaced relation between said wall members, said plates having an arc receiving slot in one end thereof, some of said

plates being spaced more closely than others, and a thin layer of boric acid between said more closely spaced plates at least along the greater portion of said plates adjacent the sides of said slots.

7. An arc extinguishing device for circuit interrupters comprising means of insulating material defining two opposed surfaces of an arc passage, said means of insulating material having a plurality of spaced grooves disposed along said opposed surfaces, a plurality of plates of conducting material disposed transversely between said opposed surfaces and having their side edges supported within said grooves, each of said plates having an arc receiving slot in one end thereof, a plurality of said plates having a part of their slot defining portions completely recessed in said means of insulating material to prevent an arc established adjacent said recessed portions from striking thereto, at least the opposed surfaces of said insulating material defining said arc passage being impregnated with a material which gives off a gas when acted upon by an arc to repel the arc for preventing sustained intimate contact of the arc with said insulating material.

8. In an arc extinguishing device for circuit interrupters comprising a pair of spaced wall members of insulating material, said wall members having a portion of their opposed surfaces adjacent one end tapering towards each other to provide a converging arc receiving passage, a plurality of spaced metallic plates disposed between said wall members, said plates having a V-shaped slot in one end thereof and considerable portions thereof defining the sides of said slots completely embedded in said tapering portions of said wall members for preventing an arc from striking to said embedded portions, at least the opposed surfaces of said wall members being impregnated with a material which gives off a gas when acted upon by an arc to repel the arc for preventing sustained intimate contact of the arc with at least said tapering portions of said wall members.

9. In an arc extinguishing device for circuit interrupters comprising a pair of spaced wall members of insulating material, said wall members having a portion of their opposed surfaces adjacent one end tapering towards each other to provide a converging arc receiving passage, a plurality of spaced metallic plates disposed between said wall members, said plates having a V-shaped slot in one end thereof and considerable portions thereof defining the sides of said slots completely embedded in said tapering portions of said wall members for preventing an arc from striking to said embedded portions, at least the opposed surfaces of said wall members being impregnated with a solution of boric acid to provide a flow of gas towards the arc when the arc impinges against said wall members to prevent sustained intimate contact of the arc with said wall members.

10. An arc extinguishing device comprising a plurality of plates of conducting material for extinguishing an arc, a pair of wall members disposed on opposite sides of said plates of conducting material for holding said plates in spaced relation with respect to each other and for guiding the arc into said plates, said wall members being composed of cold molded material including asbestos fibre and an inorganic binder and being impregnated with a material which gives off gas when acted upon by an arc for preventing

the arc from maintaining sustained intimate contact with said wall members.

11. An arc extinguishing device comprising a plurality of plates of conducting material for extinguishing an arc, a pair of wall members disposed on opposite sides of said plates of conducting material for holding said plates in spaced relation with respect to each other and for guiding the arc into said plates, said wall members being composed of cold molded material including asbestos fibre, hydrated lime and powdered silicate and being impregnated with a material which gives off gas when acted upon by an arc for keeping the arc out of sustained intimate contact with said wall members.

12. An arc extinguishing device comprising a plurality of plates of conducting material for extinguishing an arc, a pair of wall members disposed on opposite sides of said plates of conducting material for holding said plates in spaced relation with respect to each other and for guiding the arc into said plates, said wall members being composed of cold molded material including 40% asbestos fibre, 38% powdered silicate and 22% hydrated lime and being impregnated with a solution of boric acid to provide a flow of gas towards the arc when the arc impinges against said wall members to prevent the arc from making sustained intimate contact with said wall members.

13. An arc extinguishing device comprising a plurality of plates of conducting material for extinguishing an arc, a pair of wall members disposed on opposite sides of said plates of conducting material for holding said plates in spaced relation with respect to each other and for guiding the arc into said plates, said wall members being composed of cold molded material including asbestos fibre and Portland cement and being impregnated with a material which gives off gas when acted upon by an arc for keeping the arc from making sustained intimate contact with said wall members.

14. An arc extinguishing device comprising a

plurality of plates of conducting material for extinguishing an arc, a pair of wall members disposed on opposite sides of said plates of conducting material for holding said plates in spaced relation with respect to each other and for guiding the arc into said plates, said wall members being composed of cold molded material including 50% asbestos fibre and 50% Portland cement and being impregnated with a solution of boric acid to provide a flow of gas towards the arc when the arc impinges against said wall members to prevent the arc from making sustained intimate contact with said wall members.

15. An arc extinguishing device comprising a plurality of plates of conducting material for extinguishing an arc, a pair of wall members disposed on opposite sides of said plates of conducting material for holding said plates in spaced relation with respect to each other and for guiding the arc into said plates, said wall members being composed of cold molded material including asbestos fibre, Portland cement and barytes and being impregnated with a material which gives off gas when acted upon by an arc for keeping the arc out of sustained intimate contact with said wall members.

16. An arc extinguishing device comprising a plurality of plates of conducting material for extinguishing an arc, a pair of wall members disposed on opposite sides of said plates of conducting material for holding said plates in spaced relation with respect to each other and for guiding the arc into said plates, said wall members being composed of cold molded material including 50% Portland cement, 35% asbestos fibre and 15% barytes and being impregnated with a solution of boric acid to provide a flow of gas for repelling the arc when the arc impinges against said wall members and thereby preventing the arc from making sustained intimate contact with said wall members.
